LIQUID FUEL BURNING APPARATUS

Frank O. Cole, Detroit, Mich., assignor to The Timken-Detroit Axle Company, Detroit, Mich., a corporation of Ohio

Application December 26, 1935, Serial No. 56,283

8 Claims. (Cl. 158—4)

This invention relates to improvements in apparatus for combusting liquid fuel of the character which have come to be generally known as the rotary wall flame type of burner, and it is 5 more especially concerned with improvements in mixing devices commonly called grilles for mixing the elements of combustion.

A requisite for the efficient and complete combustion of fuel oils in all rotary wall flame burners, 10 and especially in those incorporating the Powers method of fuel and air distribution, as fully described in the copending application of Milton A. Powers, Serial No. 729,928, filed June 9, 1934, in which large oil droplets are flung outwardly from 15 a central distributing mechanism toward an impact wall, where they are broken up into small, minute particles and mixed with a stream of air also directed outwardly from the central distributing mechanism, but in a separate layer, is 20 that the impact wall must be maintained at a sufficiently high temperature during normal operating conditions to completely vaporize the fuel oil. Failure to maintain such a condition results in the unvaporized portion of the oil collecting on the impact wall and flame ring and the 25 igniters in the form of carbon deposits. These deposits, if allowed to grow, seriously hamper the efficiency of the burner and eventually cause failure.

Fuel oils are classified as Nos. 1, 2, 3, 4, 5, etc., the No. 1 being the highest grade in the sense 30 that it completely burns at a comparatively low temperature and costs the most. Hence the lower the grade of oil a burner will efficiently burn, the greater is its commercial success. Burners for commercial, domestic use must be able 35 to efficiently burn all grades of No. 2 oil and preferably No. 3 oil.

In burners not equipped with grilles, the flame, 40 under ideal conditions, burns from the top edge of the impact wall; however, such ideal conditions are not attainable in practice, due to variations in operating conditions, and hence to prevent the flame from burning below and on the 45 inside of the impact wall, the burner is usually adjusted so that the flame will burn slightly above and to the rear of the impact wall. Such flames are usually very high and thin and their hottest point is relatively remote from the impact wall. 50 Since the intensity of heat derived at a given point by radiation, is inversely proportional to the square of the distance between the point and the source, it is evident that under these conditions the impact wall will not absorb a great deal of 55 heat by radiation. It has been found, as a mat-

ter of fact, that the impact wall of even metal flame rings of such installations is only maintained at a temperature sufficient to completely vaporize No. 1 fuel oils and in some instances, a 5 very good grade of No. 2 oil.

The first grilles applied to a domestic fuel oil burner were those illustrated in the Forrest A. Heath Patent No. 1,886,675, and although the efficiency of the burners to which they were applied was materially increased, the limitations of such 10 burners, by reason of the ceramic material from which they were made and from which also the flame ring was made, are generally known. Hence the present discussion is confined to metallic grilles such, for example, as illustrated in the 15 copending John A. Wilson application, Serial No. 682,374, filed July 27, 1933.

The Wilson metal grille, although primarily designed to make the flame shorter and bushier, 20 incidentally increases the temperature of the flame ring by decreasing the distance between the source of heat and the flame ring, thereby increasing the rate of heat radiation to the flame ring. Also, in this grille assembly some of the 25 hot products of combustion are deflected toward the back of the flame ring and thus assist the radiated heat. It has been found that with the Wilson metal grilles assembled in a burner of the character shown in Powers application Serial 30 No. 729,928, the impact wall and flame ring are maintained at a temperature sufficient to completely vaporize the good grades of No. 2 oil; however, in some localities the specification of No. 2 oil is not strictly adhered to, with the result that 35 very poor grades of No. 2 oil are attempted to be burned and carbon deposition usually occurs.

My invention is designed as an improvement over the apparatus disclosed in the above-noted Wilson application, and a primary object is to provide grilles for an oil burner which will maintain 40 the impact wall and the flame ring at a sufficiently high temperature to efficiently burn Nos. 2 and 3 oils and good grades of No. 4 oils.

A further object is to provide a grille assembly 45 for a rotary wall flame burner having a metal flame ring, of such construction that it may be placed upon the flame ring in such manner that a maximum of radiated and convected heat will be absorbed thereby.

A further object is to provide a grille adapted 50 to be placed in very close proximity to the upper edge of a fuel burner impact wall or flame ring, whereby the hottest portion of the flame is relatively close to the flame ring.

A further object is to provide grilles for a grille 55

ring adapted to be placed on top of a fuel burner impact wall or flame ring and in relatively close proximity thereto, the grilles being adapted to be placed upon the ring in two different positions, and designed to increase or decrease the operating temperature of the flame ring, depending upon which position the grilles are placed.

A further object is to provide a grille adapted to be positioned on the upper edge of a rotary wall flame burner impact ring and comprising a series of troughs and openings, and to equip it with supporting means whereby the grille may be positioned on the impact ring in relatively close relation thereto and with the troughs either upright or inverted.

A further object is to provide attaching means on a grille having a series of troughs and openings, of such nature that said grille may be attached to its supporting member with the troughs of the grille in upright or inverted position.

The above and further objects will more fully appear from the following description and appended claims when considered in connection with the accompanying drawing wherein:

25 Figure 1 is a vertical sectional view taken substantially diametrically through a furnace or boiler in which is installed a rotary wall flame burner of the type herein contemplated and incorporating the grille assembly of my invention;

30 Figure 2 is an enlarged view in perspective of the grille of my invention;

Figure 3 is a view of one of the grille supports of Figure 2 before bending;

35 Figure 4 is an enlarged view of the grille of my invention mounted upon a flame ring with the troughs in upright position; and

Figure 5 is a view identical with Figure 4 with the exception that the grille is mounted in inverted position.

40 Referring now to the drawing, wherein like reference characters refer to like parts wherever they occur throughout the several figures, and with particular reference to Figure 1, an oil burner generally indicated at A is centrally mounted in a hearth B which closes the lower portion of the combustion chamber in a furnace or boiler C. The burner A comprises a motor 1 which drives a distributing head 3 and a fan 5. Oil is supplied to the distributor head 3 from a suitable source through the inlet pipe 7 and is flung outwardly in streams by centrifugal force, due to rotation of distributing head 3, through the flinger tubes 8. Air is supplied to the fan blades 11 of fan 5, through the apertured air collar 13, the quantity thereof being controlled by the correspondingly apertured adjustable air gate 15. The burner is substantially identical with that illustrated in the Alden and Powers Patent No. 1,882,694, and for more detailed information, 45 reference may be had thereto. In this instance, however, the tubes are inclined upwardly and outwardly, with the result that the oil droplets take an upwardly curving trajectory.

The fan 5, as illustrated, is more fully explained and described in the copending application of John A. Wilson, Serial No. 22,246, filed May 18, 1935. The lower portion of the burner A is surrounded by a shield 17 which is for the purpose of preventing over-heating of the motor, 50 and it is also more fully described in the last-mentioned Wilson application.

The hearth B comprises a thick layer of ceramic or refractory material 19 which is supported on a supporting plate 21. The supporting plate 75 is in turn supported upon a ring 23 of angular

section, which is rigidly secured to the inner wall of furnace C. Plate 21 also supports the burner A and shield 17. Placed on top of hearth B and disposed inwardly of the periphery of the combustion chamber of furnace C is a flame ring assembly 5 D, here illustrated as comprising a series of thin metallic segments placed end to end and connected together to define a continuous or endless flame ring. These segments are more fully described in the copending application of 10 Milton A. Powers, Serial No. 620,373, filed July 1, 1932, and suffice it to say here that they comprise an air deflecting surface 25, a groove or gutter 27 and an impact wall 29. However, if desirable, instead of the flame ring assembly D, a pair of 15 upright continuous metal strips having heights equal to the height of the impact wall 29 and the height of the point of juncture of the groove 27 and the deflecting surface 25 may be used, without departing from the spirit of my invention. 20 This latter assembly is more fully disclosed in the copending application of Milton A. Powers, Serial No. 747,220, filed October 6, 1934. In either event the disc-like blast of air is deflected upwardly by the inner wall to the region of the 25 impact wall impinged by the fuel.

A pair of igniters E are positioned substantially diametrically opposite each other and in close proximity to the flame ring D, and are provided with electrodes 31 which terminate in close proximity to the impact wall 29 of said flame ring, thus providing a pair of spark gaps. Electrical energy for producing the sparks is provided by the transformer F, the circuit between the electrodes being completed by the metallic flame ring. 35

Resting on top of the impact wall 29 of flame ring D is a grille assembly G, which comprises a series of individual grilles 33 (see Figure 2). The grilles 33 correspond to those disclosed in the above mentioned Wilson application and are 40 preferably made of sheet metal having a high heat resistance and also high thermal conductivity and each of them is formed from a flat sheet of metal by certain cutting and folding steps. Grilles 33 comprise a rectangular box-like 45 structure 35, the ends and sides of which are produced by bending the edges of the blank upwardly. The box is open at the top and has a series of lateral openings 37 extending from side to side of the box. The openings are formed 50 by making a series of I-shaped cuts in the base of the box and then folding the metal upwardly from the base and in this manner simultaneously forming a series of transverse troughs 39.

At each end of the box 35 are grille supports 55 41 which are also preferably made of sheet metal having a high heat resistance and thermal conductivity. Each support 41 is preferably, though not necessarily, made from a flat sheet of metal by certain cutting and bending operations. Figure 3 illustrates one of the supports after cutting but before bending it into final form. In the finished state supports 41 comprise a flat surface 43 having a substantially rectangular shape with two adjacent corners thereof cut off as at 45, to 60 provide bearing faces, and with separate inwardly bent fingers 47. Fingers 47 are bent along their outer portions to take the slope of the bearing portions 45. The flat surfaces 43 of supports 41 are spot-welded substantially symmetrically to 70 the ends of the box-like section 35 of grilles 33 so that the portions 45 of the supports 41 at each end of the grille are in alignment as are also the upper bent portions of the fingers 47. As seen in Figures 4 and 5 fingers 47 are spaced from 75

bearing faces 45 a distance approximately equal to the thickness of the impact wall.

In assembling the grille on the impact wall of the flame ring the upper bent portions of fingers 47 are positioned on one side of said impact wall and the bearing faces 45 are placed on the other side. In this manner each grille has a two-point support on the impact wall. The angle of bearing faces 45 is such that when the grille 10 is in assembled position the plane of the upper or lower edge of the box section 35 is substantially normal to the path of air flow passing over the top of the impact wall, as seen in Figures 4 and 5.

15 Due to the fact that bearing faces 45 and fingers 47 are provided on both the upper and lower sides of each grille, the grilles may be assembled on a flame ring with the troughs 39 of the grille in either upturned position as shown in Figure 4, 20 or in downturned position as illustrated in Figure 5. The desirability of this optional mode of assembly will appear hereinafter.

It has been demonstrated in actual practice 25 that if carbon deposition occurs with the grilles in the position of Figure 4, i. e., with the troughs upturned, a reversal of the grilles to the position illustrated in Figure 5 will, in addition to eliminating carbon deposition, actually burn off the carbon which had previously collected. With my 30 improved grille assembly this inverting is only necessary where very poor grades of fuel oil are encountered.

There are several theories as to what takes 35 place during normal operation of a burner in and about the grille ring, but for the sake of clarity, I will confine my discussion to only one of them. It is elementary that when air is mixed with vaporized fuel oil, combustion will not take place, nor will it be supported until a certain 40 place, nor will it be supported until a certain "critical mixture" is obtained. If a given quantity of air is directed into a zone of vaporized oil at a relatively high velocity, combustion will not take place at the point where the air meets the vaporized oil, for there will be insufficient mixing. The "critical mixture" will occur at some 45 point removed from the point of contact and in the direction of the air flow. Where there is no impedance presented to the flow of the mixed air and vapor the point of critical mixing will occur at a point relatively remote from the zone of vaporized fuel. If a baffle is placed in the line of the air and vapor flow it will shorten the distance between the point at which the "critical mixture" is obtained and the initial joinder 50 of the air and vapor. The closer this impedance is placed to the point of joinder the less the distance to the point of "critical mixture" will be.

In Figure 4 I have indicated the path of the oil droplets from the finger tubes 9 of the oil 55 distributing mechanism by small circles and the path of the vaporized oil by small arrows. I have likewise indicated the path of the air flow from the air distributing mechanism by means of dash lines. When the oil droplets strike the impact wall 29 they are immediately broken up into minute particles or vaporized (assuming the apparatus has come up to operating temperature) and will be carried upward by the air stream which is deflected by the deflecting portion 25 of the flame ring segments. The mixture of air and oil vapor at the top of the impact wall 29 is not sufficient to support combustion and if the grille 33 were not present the point of "critical mixture" would be substantially above the impact wall. However, with the grille 33 assem-

bled in the position illustrated, a portion of the air and oil vapor mixture will strike the underside of the troughs 39 and will be deflected, some of the deflected mixture passing upwardly through the openings 31, some bouncing back and causing eddies, some passing over the ends and a good portion being directed toward the back of the flame ring. Thus, the grilles constitute mixing devices, and by using them the mixing of the air and oil vapor is speeded up and the point of "critical mixture" is obtained in a much shorter distance. In operation the grilles 33 get very hot, becoming a dull cherry red and due to their closeness to the flame ring the radiant heat from them aids the deflected hot gases and mixture, in maintaining said flame ring at a comparatively high oil vaporizing temperature. Also, since the flame which burns from the top of the grilles is relatively close to the flame ring it heats the zones in and around the ring and thus aids and abets this heating.

Referring now to Figure 5, substantially the same conditions and functions take place with the exception that, with the troughs 39 inverted, a greater quantity of air and oil vapor mixture 25 and also hot gas of combustion are deflected towards the back of the flame ring. The grilles, accordingly, have a greater "mixing power". This is accounted for by the confining action of the sides and ends of the troughs, and the deflection of the mixture is confined within a smaller region. Thus faster mixing is obtained and although there is visibly little or no flame under the grilles, or back of the flame ring, combustion 30 actually takes place in said region. Also, there is more heat radiated to the flame ring, as in this instance heat from the sides and end portions of the trough is added to that of the bottom of the trough.

It is evident from the above and foregoing description that the grille assembly of my invention provides for a more efficient operation of oil burners of the rotary wall flame type and that I have provided novel mounting means for grilles 45 whereby they may be positioned relatively close to a flame ring and may be in either upright or inverted position. Moreover, if desired, supports 41 may be made integral with the grilles.

Although I have illustrated supports 41 as being secured to the grilles in symmetrical relationship, so that the grilles will assume a constant angularity with respect to the flame ring irrespective of whether they are supported in upright or inverted position, it is to be understood 55 that they may be asymmetrically mounted on bearing faces 45, and fingers 47 on one side of the grille be given a different inclination so as to dispose the grilles at different angles, without departing from the spirit of the invention.

The invention may be embodied in other specific forms without departing from the spirit or essential characteristics thereof. The present embodiment is therefore to be considered in all respects as illustrative and not restrictive, the scope 65 of the invention being indicated by the appended claims rather than the foregoing description, and all changes which come within the meaning and range of equivalency of the claims are therefore intended to be embraced therein.

In the appended claims the term "carbureting member" is intended to embrace the assembly of parts making up the carbureting ring irrespective of whether it be made of segments or continuous rings.

What is claimed and desired to be secured by United States Letters Patent is:

1. In a liquid fuel burning apparatus of the wall flame type, having a substantially horizontal hearth surrounded by a wall to be heated, a substantially endless carbureting member located above the hearth and adjacent said wall, said member having a fuel impact surface facing toward the center of the hearth, a distributor head projecting upwardly through said hearth center and spaced from said carbureting member; said head having means for delivering a disc-like blast of air outwardly along the hearth toward said carbureting member, said head further comprising means for projecting liquid fuel toward said impact wall in unatomized condition from the head, said carbureting member embodying a surface operable to deflect said blast of air into proximity to said impact wall, and an intermixing device mounted in a predetermined position on said carbureting member and operable to intimately intermix oil vapors and air currents rising above said carbureting member, said intermixing device being movable into a second predetermined position on said carbureting member, said intermixing device when in said second position having an inter-mixing power that is considerably different from that when it is disposed in said first-named position.
2. The liquid fuel burning device described in claim 1, wherein said intermixing device comprises a substantially flat member having sides of considerable area and is provided with a plurality of open-sided pockets in one of its sides.
3. In combination with a carbureting member having a comparatively thin, substantially upright impact wall, a generally flat grille assembly having a frame, said frame having a supporting device at each end thereof operable to fit over the upper edge of said impact wall and rigidly support said grille assembly, each of said supporting devices comprising a pair of finger-like elements projecting beyond the planes of said frame in one direction, and adapted to straddle the upper edge of said impact wall, and a pair of finger-like elements projecting beyond the planes of said frame in the opposite direction, whereby said grille may be removed from said impact wall and supported thereon in an inverted position.
4. The construction described in claim 3, wherein each of said pairs of fingers comprises two flat members, one finger of each pair being disposed substantially normal to said impact wall and the other being disposed substantially parallel to said impact wall when said grille is disposed in operative position thereupon.
5. The construction described in claim 3, wherein said pairs of finger-like members are symmetrically disposed with respect to said grille, whereby the latter will be supported at a predetermined inclination with respect to said impact wall irrespective of the position in which it is mounted on said impact wall.
6. In combination with a liquid fuel burning apparatus having a comparatively thin substantially upright impact wall, a grille structure comprising a flat body member, a flat supporting member secured to each end of said body member and having an inclined bearing face, said supporting member also having a finger disposed substantially normal to the plane thereof and extending in a direction substantially parallel to said bearing face, said grille being adapted to be mounted on said impact wall with said bearing faces and said fingers straddling the upper edge thereof.
7. The device described in claim 5, wherein said supporting members extend in both directions away from said body member and thereby adapt said grilles for support in an upright or an inverted position upon said impact wall.
8. In a liquid fuel burning apparatus of the wall flame type, having a substantially horizontal hearth surrounded by a wall to be heated, a substantially endless carbureting member located above the hearth and adjacent said wall, said member having a fuel impact surface facing toward the center of the hearth, a distributor head projecting upwardly through said hearth center and spaced from said carbureting member; said head having means for delivering a disc-like blast of air outwardly along the hearth toward said carbureting member, said head further comprising means for projecting liquid fuel toward said impact wall in unatomized condition from the head, said carbureting member embodying a surface operable to deflect said blast of air into proximity to said impact wall, and an intermixing device mounted in a predetermined position on said carbureting member and operable to intimately intermix oil vapors and air currents rising above said carbureting member, said intermixing device having two substantially flat sides of appreciable area, one of which faces the oncoming combustible mixture and the other of which faces oppositely thereto, said device having a set of open-sided pockets provided thereon and facing the oncoming combustible mixture, for intimately intermixing the components of the latter.
